E. G. BALLINGER
RECORDING DIAL FOR RADIO SETS

Filed Aug. 7, 1925

Edgar G. Ballinger
James L. Norris Attorney

UNITED STATES PATENT OFFICE.

EDGAR G. BALLENGER, OF ATLANTA, GEORGIA.

RECORDING DIAL FOR RADIOSETS.

Application filed August 7, 1925. Serial No. 48,812.

This invention relates to radio apparatus and proposes the construction of a recording dial for tuning units such as the coils, couplers, and condensers commonly employed in radio receivers, in which provision is made for recording the names of transmitting stations or other data, with reference to suitable indicia associated with the dial so that the angular position of the latter, when a station is tuned in, may be subsequently re-located when it is again desired to hear the station without the usual uncertainty and time-consuming manipulation incident to the act of tuning in.

Other objects of the invention relate to the form and construction of the indicating means and its co-relation with the dial whereby maximum space is made available for the recording of the station names or other data, and the invention also concerns itself with such novel and specific features of construction and arrangement of parts as will appear in the following description of an illustrative embodiment of the invention.

In the drawings:-

Figure 1 is a front elevation of one form of my invention.

Figure 2 is a transverse section taken along the line 2--2 of Figure 1.

Figure 3 is a front elevation showing a slightly modified form of my invention.

Figure 4 is a transverse section taken along the line 4--4 of Figure 3.

Figure 5 is a front elevation showing still another form of the invention.

Figure 6 is a vertical section taken along the line 6--6 of Figure 5.

Referring now in detail to the several figures, and first advertiring to that form of the invention illustrated in Figures 1 and 2, the numeral 1 represents the panel-board of a radio receiver through which projects the shaft 2 of any suitable tuning device such as a coil, coupler or variable condenser.

A dial 3 is secured to the projecting end of the shaft 2 in any suitable manner, as for instance, by the set screw 5. The dial, in the illustration is provided with a knob 5 by means of which it may be turned simultaneously with the adjustment of the tuning unit. It is obvious that in so far as the rotation of the dial is concerned the knob is not essential being usually omitted in re-

ceiving sets of the super-heterodyne type in which the tuning unit is moved by means independent of the dial, the latter rotating with the shaft of the tuning unit. The dial 3 is enclosed within a casing 6, the latter being dished to form a chamber in which the dial is freely rotatable and having a flange 7 by means of which the casing is secured to the panel. A central aperture in the casing permits the protrusion of the knob 5. The front wall of the casing 6 is cut away diametrically on opposite sides of the shaft 2 to form windows 8 and 9 thereby giving access to the surface of the dial which is prepared so that it may receive and render visible lead pencil or ink notations that may be inscribed thereupon. A part of the casing adjacent the windows is shaped to form pointers 10 and 11 which serve as indicators to which the inscribed notations may be referred.

In order that the maximum number of notations may be placed upon the dial and that they may at the same time be sufficiently large to be plainly legible, it is preferred that there be room for two series of said notations, one adjacent the center of the dial and the other adjacent its periphery. The windows 8 and 9 are so arranged that the former overlie the peripheral portion of the dial while the latter overlies that portion adjacent the center.

Although most tuning devices have an operative range of 180°, it is desirable to utilize the entire surface of the dial for the inscription of notations. To accomplish this the windows are duplicated on opposite sides of the axis of rotation of the dial and stations which are adjacent according to wave length are notated on opposite sides of the face of the dial so as to be visible through oppositely arranged windows.

In Figures 3 and 4 the casing 6 is omitted but an equivalent indicating device is provided in the form of a bent wire or sheet metal band 12 arranged to pass diametrically across the face of the dial and being secured to the panel at opposite sides of the dial. Said band is provided with windows 13 and 14 corresponding respectively to the windows 8 and 9 in the casing 6 and being arranged with similar indicating pointers 15 and 16.

In that form of the invention shown in

Figures 5 and 6 the dial is geared in two to one relation to the tuning unit so that it makes a complete revolution while the tuning unit moves through its operative range 5 of 180°. The tuning unit is in this instance represented as a variable condenser 17 the rotor shaft of which is provided with a gear 18 meshing with a half-sized gear 19 mounted on a stub-shaft 10 20, the latter projecting through the panel and carrying the dial 21. Said dial is here shown as being enclosed by a casing 22 which differs from the casing shown in Figure 1 only in the fact that the windows 23 15 and 24 are provided on one side of said casing, this being the sole change necessitated by the fact of the complete rotation of the dial 21. It is apparent that stations adjacent with respect to wave length may be 20 notated in the dial consecutively in staggered order one being visible through the peripheral window and the other through that window adjacent the center of the dial.

In operation, a station having been tuned 25 in, the name of the station is inscribed adjacent the end of the most convenient of the indicating pointers. When it is desired again to tune in upon the same station it is merely necessary to move the dial until the 30 inscribed name of the station is in its original position with respect to the indicating pointer. It is obvious that once the dial has been inscribed with the names of stations 35 previously tuned in, the combined dial and indicator becomes a station selector by means of which stations may be efficiently tuned in by a single setting of the dial with respect to the indicator, avoiding the uncertainty and guess-work which is incidental 40 to tuning in, as ordinarily practiced.

While I have herein illustrated and described what I believe to be a preferred and practical form of my invention it is to be understood that such changes may be made 45 in the construction and arrangement of parts as are consistent with the terms of the appended claims.

Having described my invention what I

claim as new and desire to secure by Letters Patent, is:

1. In radio apparatus, a station selector comprising a dial adapted to be mounted upon the rotor of a tuning unit, said dial having a surface adapted to receive written matter, and an indicator fixedly mounted with respect to said dial having a space bridged by a pointer carrying member to form a plurality of windows arranged side by side in a radial direction, exposing the inscribed surface of said dial in sequential portions, in peripheral and central zones. 50

2. In radio apparatus, a station selector comprising a dial adapted to be mounted upon the rotor of a tuning unit, said dial having a surface adapted to receive written matter, and an indicator fixedly mounted with respect to said dial having a plurality of spaces arranged diametrically, an equal number on each side of said dial, and pointer carrying members bridging spaces to 55 form a plurality of windows exposing the inscribed surface of the latter simultaneously upon opposite sides in peripheral and central zones. 60

3. In radio apparatus, a station selector comprising a dial adapted to be mounted upon a rotor of a tuning unit, said dial having a surface adapted to receive written matter, and an indicator extending across the face of said dial and fixed with respect 75 thereto, said indicator being formed of a wire bent to form a central loop adapted to surround the stem of the dial knob, and bent at its extremities to form loops for the reception of securing means, said indicator 80 being formed with elongated loops intermediate said central and terminal loops, and pointer carrying transverse members bridging said elongated loops transversely at intermediate points forming a plurality of 85 windows symmetrically spaced on diametrically opposite sides of said dial. 90

In testimony whereof I have hereunto set my hand.

EDGAR G. BALLENGER.
